Specification for Design.

Patented Dec. 6, 1921.

Application filed November 4, 1920. Serial No. 421,775. Term of patent 3½ years.

To all whom it may concern:

Be it known that I, ZYGMUND SOBCZAK, a citizen of the United States, residing at Metz, in the county of Presque Isle and State of Michigan, have invented a new, original, and ornamental Design for a Picture-Frame, of which the following is a specification, reference being had to the accompanying drawing, forming part thereof.

The figure represents a perspective view of a picture frame, showing my new design.

I claim:

The ornamental design for a picture frame as shown.

ZYGMUND SOBCZAK.
